UNITED STATES PATENT OFFICE.

THOMAS SMITH DUNCAN, OF WESTMINSTER, LONDON, ENGLAND, ASSIGNOR TO
VICKERS LIMITED, OF WESTMINSTER, LONDON, ENGLAND.

STARTING OF INTERNAL-COMBUSTION ENGINES.

1,309,722.

Specification of Letters Patent. Patented July 15, 1919.

Application filed April 25, 1919. Serial No. 292,653.

To all whom it may concern:

Be it known that I, THOMAS SMITH DUNCAN, a subject of the King of Great Britain, residing at Vickers House, Broadway, Westminster, in the county of London, England, have invented certain new and useful Improvements in or Relating to the Starting of Internal-Combustion Engines, of which the following is a specification.

- 10 This invention relates to apparatus for starting internal combustion engines of the kind in which a clutch member is moved into engagement with a clutch member on the engine shaft, by means of a helically 15 grooved or screw threaded spindle or the like, the arrangement being such that after the engine has been started, it will over-run the helically grooved spindle so that the engaging clutch members are automatically 20 disengaged. The present invention has particular reference to the starting of aircraft engines, which are arranged in pairs, for example one pair on each side of the fuselage 25 naselle.
- According to this invention we interpose between each pair of engines a starting apparatus comprising two co-axially arranged clutch members adapted to move into engagement with clutch members associated 30 with engine shafts by means of a helically grooved or screw threaded spindle which is rotated in any appropriate manner. The helically grooved spindle may be rotated in either direction by an electric motor through 35 worm gearing and one or other of the said clutch members will be moved into engagement with the clutch members on the engine shaft according to the direction of rotation of the electric motor and the helically 40 grooved spindle. Thus the engines may be started in succession and after each engine has started, the engaging clutch members will be automatically disengaged by the engine overrunning the helical grooved spindle 45 and the electric motor. In some cases the clutch members may be moved together in opposite directions to engage simultaneously with the engine shaft, so that the engines are started together.
- 50 In order that the said invention may be clearly understood and readily carried into effect the same will now be described more fully with reference to the accompanying drawings, in which:—

Figure 1 is a diagrammatic sectional view 55 of one construction for starting in succession a pair of engines having coaxial shafts.

Fig. 2 is a sectional view of a modified construction also for successively starting a 60 pair of engines having co-axial shafts.

Fig. 3 is a vertical sectional view taken on the line 3—3 of Fig. 2.

In the examples shown A and B represent the co-axial shafts of the two engines. Between the two ends of the shafts A, B 65 and co-axial therewith is a worm wheel C mounted in a suitable bearing and adapted to be rotated by a worm D which is actuated in any suitable manner such as for example by a small electric motor (not shown in 70 Fig. 1). In Fig. 1, a screw spindle E having a helical thread or groove E' of quick pitch extends through and engages with a screw threaded portion at the center of the worm wheel C. On the ends of the screwed spindle 75 E are friction cone clutch members F and G, adapted to engage respectively with clutch members H I on the ends of the engine shafts A B. Supposing it is desired to start the engine, the worm wheel C is rotated in one direction and the spindle E is thereby moved longitudinally so as to cause the clutch member (say F) to engage with the member H on the shaft A so as to rotate that shaft and thus start the engine.

When the engine has been properly started the shaft A will over-run the starting motor and the spindle E in rotating faster than the worm wheel C moves in the opposite longitudinal direction and the clutch member F is thereby automatically disengaged from the member H. The other engine can then be started by rotating the worm wheel in the opposite direction whereupon a similar operation takes place to that above described.

Spring brakes J bear on the clutch members F G to prevent rotation of the spindle E until either of the clutch members F or G actually engages with either the members 100 H or I. In this arrangement the shafts of the engines rotate in opposite directions.

In the construction shown in Figs. 2 and 3 the worm wheel C is free on the spindle E but is gripped between two plates C' C' 105 keyed to the spindle E which plates bear against suitable surfaces C² C² on the worm wheel so as to provide a friction drive for

- transmitting the motion of the worm wheel to the spindle when the worm is operated by the electric motor K which is conveniently supported in a part of the casing of the 5 gearing, see Fig. 3. The spindle E is provided at its ends with helically grooved portions E² with which engage suitably formed sleeves F, G having end teeth F', G', forming dog or jaw clutch members for engaging 10 with similar clutch members H' and I' on the ends of the co-axial shafts A and B of the two engines, when the worm wheel is rotated in one direction or the other. Spring brakes J J bear on the said clutch- 15 sleeves to prevent rotation of the same until actually in engagement with the clutch members H I. The rotation of the spindle E in one direction causes one of the clutch sleeves say F, to be thrust outwardly into engagement with the member H by reason of the interengaging helical grooves or the like and when engagement is effected the sleeve is no longer held against rotation by the 20 springs with the result that the engine shaft A is rotated and the engine started. When the engine shaft A overruns the starting motor K the clutch member F, in rotating faster than the spindle E is automatically disconnected from the engine shafts. When 25 the motor K and the spindle E is rotated in the opposite direction, the other clutch sleeve G is moved outwardly to start the other engine and is automatically disengaged in the manner aforesaid.
- 30 The apparatus may be devised for starting two engines simultaneously in which case portions such as E² are formed with oppositely cut helical grooves and the clutch sleeves are formed accordingly, so that rotation of the spindle in one direction moves the clutch members simultaneously to effect 35 starting of the engines together.
- What I claim and desire to secure by Letters Patent of the United States is:—
- 40 1. Starting apparatus for a pair of internal combustion engines, comprising two co-axially arranged clutch members adapted to be moved into engagement with clutch members associated with the engine shafts by means of a helically grooved or screw-threaded spindle, which is adapted to be rotated 45 to effect the necessary movement of the clutch members when starting the engines.

gines, which clutch members will after the engine has been started be automatically disengaged by the engine overrunning the helically grooved or screw threaded spindle substantially as described. 55

2. Starting apparatus for a pair of internal combustion engines comprising two clutch members, a helically grooved spindle or the like for moving the clutch members into engagement with the engine shafts, and an electric motor for rotating the spindle to cause the one or other of the clutches 60 to engage with the corresponding engine shafts according to the direction of rotation of the motor substantially as described. 65

3. Starting apparatus for a pair of internal combustion engines comprising a spindle having screw threads or helical grooves at its ends to receive clutch members which when the spindle is rotated will be moved longitudinally to engage with the engine shafts, substantially as described. 70 75

4. Starting apparatus for a pair of internal combustion engines comprising a spindle, two clutch members mounted on opposite helically grooved ends of the spindle, and means for holding the members against rotation until said clutch members engage other clutch members on said engine shafts, substantially as described. 80

5. Starting apparatus for a pair of co-axial internal combustion engines comprising a screw threaded or helically grooved spindle adapted to be rotated by plates carried thereon, said spindle having clutch members mounted on its ends adapted to move longitudinally and engage the engine shaft when the spindle is rotated, substantially as described. 85 90

6. Starting apparatus for a pair of co-axial internal combustion engines, comprising a spindle having screw threads or helical grooves at its ends upon which clutch members are mounted, one of said members adapted to engage the clutch member of one of said engines, when the spindle is rotated in one direction, and the other of said clutch members adapted to engage the clutch member of the other of said engines when the spindle is rotated in the opposite direction. 95 100

In testimony whereof I affix my signature.

THOMAS SMITH DUNCAN.
